(57) **CLAIM**

The ornamental design for a roll-top shield for weighing scales, as shown and described.

DESCRIPTION

FIG. 1 is a perspective view showing my new design of the roll-top shield for weighing scales in a closed position;

FIG. 2 is a front elevational view with the roll-top shield for weighing scales in a closed position,

FIG. 3 is a rear elevational view with the roll-top shield for weighing scales in a closed position,

FIG. 4 is a top plan view with the roll-top shield for weighing scales in a closed position,

FIG. 5 is a right elevational view with the roll-top shield for weighing scales in a closed position (the left elevational view being a mirror image of the right elevational view),

FIG. 6 is a bottom plan view with the roll-top shield for weighing scales in a closed position,

FIG. 7 is a perspective view of the roll-top shield for weighing scales shown in a partially opened position; and, FIG. 8 is a perspective view of the roll-top shield for weighing scales shown in an opened position.

The broken lines showing a weighing scale in FIGS. 1, 7 and 8 are for illustrative purposes only and do not form part of the claimed design.
